AUTOMATIC ROTOR VALVE

Vernon D. Beehler, Evanston, and Robert D. McIntosh, River Forest, Ill., assignors to The Imperial Brass Manufacturing Company, Chicago, Ill.

Application September 10, 1934, Serial No. 743,388

13 Claims. (Cl. 137—153)

Our invention relates to valves and more particularly to rotor valves for control of gas or other fluids.

The general object of our invention is to provide a single rotor valve adapted to service one or more burners, in which is incorporated an automatic control to prevent intermediate positioning of the valve between certain adjustments.

Another object of our invention is to provide a rotor valve in combination with a pressure regulator which is efficient under all conditions of temperature and pressure.

Another object is to provide a rotor valve adapted to automatically assure certain preselected adjustments, operating in combination with a pressure regulator coacting with said valve.

Another object is to provide a power control for a rotor valve which will allow adjustment at definite selected positions and prevent any intermediate adjustment between those positions by returning the valve automatically to the selected positions.

Another object is to provide a rotor valve which supplies gas selectively to a low burner adjustment and to a high burner adjustment, which is equipped with a power means acting circumferentially to prevent any intermediate adjustment between low and high burner adjustment and which will allow all stages of adjustment between low burner and off position.

A further object is to apply a tangential force to the sliding element of a rotor valve which will tend to rotate the rotor when opposed by a cam face and allow the rotating element to retain its position when bearing tangentially against the side of the cam.

A still further object is to apply a spring controlled element tangentially to the rotating member of a rotor valve whose action will be initiated by contact with a cam face on assumption by the rotor of a first preselected adjustment and continue to return the rotor to that adjustment until the cam point has rotated past the element to assume a second preselected adjustment and which will again continue to return the rotor to the first adjustment when the cam point has passed the element on reversal of the rotating motion.

Another object is to provide a rotor valve combined with a steam pressure shut-off in which the rotor and shut-off means are housed within the valve and in which the automatic features are concealed and simplified.

In pursuance of the foregoing objects we aim to provide a rotor valve housing a steam pressure regulator and a rotor member, which supplies se-

lectively a small burner alone and jointly a small burner and a large burner with a regulated gas supply and which can be set in all intermediate stages of adjustment between shut-off position and "on" position for the small burner but which cannot be set for any intermediate stages between the full "on" position for both burners and an adjustment at which the large burner is shut off, which corresponds simultaneously with a full "on" position for the small burner alone. Further objects and advantages of our invention will become apparent as the description proceeds taken in connection with the accompanying drawings which form a part of this specification.

Fig. 1 is a top view of a preferred form of the valve with the handle removed.

Fig. 2 is a section on 2—2 of Fig. 1.

Fig. 3 is a bottom view of the body on line 3—3 of Fig. 2.

Fig. 4 is a sectional view of a modification of the latch arrangement on the handle.

Fig. 5 is a top view of Fig. 4 with the handle and conical spring removed.

Fig. 6 is a sectional view on 6—6 of Fig. 7 showing a modification.

Fig. 7 is a bottom view on 7—7 of Fig. 6.

Fig. 8 is a top view of another modification showing the rotor on the outside.

Fig. 9 is a sectional view on 9—9 of Fig. 8.

Fig. 10 is a front elevation on Fig. 8 with the handle and base removed.

While our invention is susceptible of embodiment in many different forms, we have shown in the drawings and will herein describe in detail a preferred embodiment thereof, together with several modifications, with the understanding that we do not intend to limit our invention to the particular construction and arrangement shown, it being contemplated that various changes may be made by those skilled in the art without departing from the spirit and scope of the appended claims.

A need has been felt for a combined valve and regulator for fluid fired steam devices which will maintain its high efficiency under all conditions of temperature and pressure. In adapting a rotor valve to this function problems were presented in connection with regulation and control where one valve jointly serves several outlets. Steam pressure regulators operating on a diaphragm have been known, but it is felt that previously no attempt has been made to combine the benefits of a rotor valve with a steam pressure regulator in a novel, well protected manner. The principle of the rotor valve has been called upon to perform this service and the application is

devoted in part to the solution of the attendant difficulties.

Fig. 1 shows the valve in the position which it would customarily occupy on the side of a gas heated steam radiator of the type usually used for space heating purposes. A base portion 5 screws into the radiator by means of threads 6 and to it is attached the body 7 of the valve by means of screws 8. Within the body and rotatably sliding 10 thereon is a rotor 9 which is turned by handle 10 by means of stem 11 to which both are firmly attached.

Gas enters the valve at inlet 15, shown also in dotted position behind the stem in Fig. 2. 15 From the inlet the gas enters and fills the gas chamber 16 and passes around the bottom of the rotor 9 into passage 17. A short duct 18 connects the passage 17 with a curved groove or slot 19 formed on the face of the rotor. A bypass 20 also connects the gas chamber with groove 19. In the adjustment illustrated in Fig. 2 the rotor is turned so that gas is being fed to port 23 which supplies a large or high flame burner, which it is not felt necessary to show. A 25 conduit 24 conducts the gas from port 23, to which it has been delivered by groove or aperture 19, to the threaded outlet 25. A small or low flame burner, also not shown but which connects directly to the valve, is supplied by gas 30 passing into port 26, and then thru outlet 27. This port is always open when port 23 is being supplied but may continue open after port 23 35 has been closed. The position that rotor slot or groove 19 would occupy for full "off" position is shown by the dotted lines on Fig. 3. The arrow indicates the direction of movement in turning the gas on, and it will be readily seen that port 26 can be supplied before port 23 need be turned on, and that when port 23 is "on" both are necessarily 40 "on" for the particular arrangement shown in this embodiment. By the simple expedient of providing a rotor with two or more grooves, depending on the number of ports and outlets to be supplied, gas may be carried to any single port 45 opening without it being necessary to open any other port and the same principle can be carried as far as convenience will permit a multiplicity of outlets.

When the valve is in operation among its common uses is to supply fuel for generating steam in a boiler or a combination gas and steam radiator. If this be the case the base 5 may be connected to the steam reservoir so that chamber 30 will be filled with steam under whatever 50 pressure is maintained in the radiator. As the pressure increases due to the continued heating of the water in the radiator it acts against a diaphragm 31 clamped between gaskets 32 and 33 and tends to push the diaphragm toward the 55 rotor. The point will be reached where the diaphragm will close the lower end of passage 17 and correspondingly cut off the flow of gas through it. At this point gas continues to be supplied to the groove 19 by way of the bypass 60 20 and allows either or both burners, as the case may be, to continue burning but at a reduced flame, limited by the capacity of the bypass to admit the fuel gas. The flame is thus sustained at a low level until the steam pressure drops again and a retraction of diaphragm 31 permits 65 more gas to pass.

It is frequently desirable to have a means of indicating when the device is at shut-off, low flame or high flame position, as indicated on the drawings by the lettering off, low and high. To

this end the handle 10 is provided with a pointer 35, which, aided by marks on the body, indicates the corresponding position of the rotor. Slots or stops 36, 37 and 38 are formed in a head piece 40 and are adapted to receive a wedge portion 5 39 of the handle to retain the handle immovable in the respective positions of "off", "low" and "high". A coiled spring 41 acts between the bottom of 40 and a washer 42 bearing against the shoulder 43 of the handle 10. 10

For attachment of the loosely fitting handle 10 eccentrically to stem 11 a pin 45 is used. The action of spring 41 is therefore to return the handle 10 to horizontal position after tilting and to maintain the wedge 39 in any one of the 15 notches, from which it may be released for readjustment by manually pressing the end of handle 10 downward. At the same time spring 41 acts to pull the rotor 9 upward and draw the face 46 of the rotor into intimate contact with corresponding face 47 of the body so that no gas 20 will pass therebetween.

The stem may be non-rotatably attached to rotor 9 by means of screw 48 and key 49. The connection at the same time is slightly loose to 25 permit the rotor faces to adjust themselves tightly without the necessity of stem 11 being rigidly in 90 degree alignment with the rotor. To form a gas tight joint without hampering the freedom of the stem connection with the rotor, a cap screw 30 50 is screwed into the passage 17 against a washer 51.

For reasons particular to the adaptation of the device to the purpose described it is desired to have the rotor adjustable to all intermediate 35 positions between "off" position and "low" but to assure no intermediate adjustments between "low" and "high", the reason being that an adjustment slightly above "low" would permit gas 40 to pass from outlet 25 to the very large burner but in insufficient quantity for ignition, with attendant loss and danger. Accordingly a heavy spring 55 is provided, anchored at the bottom at 56 and the top end 57 protruding through slot 58 in head piece 40. 45

Tension is set in the spring 55 on assembly by twisting it the desired amount before fastening head piece 40 with its screws 44. A pin 59 is positioned in stem 10 so that as the handle is turned to "low" position the pin 59 comes into contact with the end of the already tense spring 55. From this position to "high" position the rotation is constantly against the force of spring 55 so that if the handle be released in any intermediate position it will be immediately forced 55 back to the point marked "low". There is a slot 38 at "high" position which holds the wedge 39 of the handle in full "high" position only, from which it may be released by tilting the handle 10.

In describing the operation let us assume the 60 valve is to be on "off" position. In this case the pointer 35 of the handle would point toward the bottom of the page if shown on Fig. 1 and would be engaged in slot 36. The groove in the face of the rotor would be in position somewhat as indicated by the dotted outline in Fig. 3. From this point, when the handle is disengaged by tilting it may be turned toward "low" as slot 19 is moved in the arrow direction to gradually open port 26, and an attached burner may be lit at any 65 intermediate adjustment where sufficient gas is supplied. At "low" position the wedge 39 under pointer 36 is engaged in slot 37. At this point the pin 59 comes into contact with the upward extending end 57 of spring 55 which is held under 70 75

tension in this position by the end 61 of slot. As the handle is moved from "low" toward "high" the pin 59 picks up the spring end 57 and carries it along so that if the handle is released the spring 5 immediately forces it back to the "low" position where the spring movement is halted and the conical spring 41 snaps the handle wedge into slot 37. When the handle is finally turned to full "high" position a similar snapping action engages it in slot 38, where it is held until manually released by tilting. At this adjustment the rotor groove 19 opens both ports 23 and 26 allowing gas to pass thereto from the gas chamber.

Figs. 4 and 5 show a modification of the spring return means. The rotor is attached as usual to the bottom of stem 11 and the parts held in place by conical spring 41 which is retained under tension by shoulder 70 of the stem. A heavy spring 55' is wound loosely about the stem and the upward end 57' protrudes through a slot 58' far enough to hook into a hole 71 on boss 72 of handle 10'. A wedge shaped pin 73 engages in slots 36', 37' and 38'. The bifurcated end of lever 74 slips into a groove 75 of the pin 73 by means of which it can be disengaged by lever action manually from the slots. A V shaped spring 76 acts upon the lever 74 and pushes it upward and consequently the wedge pin 73 downward into engagement with the slots. The principle of operation is the same as that previously described for the preferred form except that disengagement is accomplished by pressing a lever rather than by tilting the handle, and the pointer 35' serves solely as a direction indicator.

Figs. 6 and 7 show views of a modification of the device in which is incorporated a slightly different application of the return power means. In this arrangement a power element or force is applied more or less tangentially to the rotor means and a cam action is utilized to react with the power element. The base 5' is attached to the body 80 by screws 81 and spaced therefrom by the diaphragm 31' and a spacing ring 82. A rotor 83 turns with stem 84 and is retained in position by conical spring 85. A handle is attachable at 89. The circumference 103 of rotor 83 is extended as at 86 to form a cam face 87 and a stop shoulder 88. A disc 91 attached to a curved shank 92 slides along the face 93 of the attachment 94. Attachment 94 is relieved at 95 for disc 91 and has a boss 96 forming a positive stop for the disc at the other end. A spring 97 tends to draw the disc toward the boss.

In the position shown in Fig. 7 the valve is open with the full line position of rotor groove 100 opening into both large port 101 and small port 102. A stop pin 103 prevents further clockwise motion. The disc 91 is under tension counter-clockwise, but in the full open position shown the direction of force tends to act radially of the rotor and secure the latter in its position. As the rotor is rotated counter-clockwise to effect a closing the cam face 87 passes the disc 91 and the tension on 91 draws it out from the relieved portion 95 of the attachment 94 toward the smaller circumference 104 of the rotor which is positioned to leave sufficient space 105 between itself and the attachment so that disc 91 can slide along within it. Disc 91 acting against the cam face 87 draws the rotor counter-clockwise until the disc stops against boss 96 at which point the rotor is in "low" position, or feeding the small port 102 only. The rotor may be rotated still further in a counter-clockwise direction, unaccompanied by spring pressure until face 88 rests against pin 103 which is a full "off" position. The flow of gas

from inlet 106 to chamber 107 and thence through passage 108 to groove 100 is identical with the action of Figs. 1 to 3.

Another modification of the device in which the rotor is exposed is shown in Figs. 8, 9 and 10. The usual type of base 5" is shown separated by a diaphragm 31" from the body 125 of the valve. The face 126 of rotor 127 slides against a corresponding face 128 of body 125. The rotor is keyed to a stem 129 extending into the valve body at 130 where it is secured by a screw 131 and washers 132. A spring 133 bearing against washer 134 and shoulder 135 of stem 129 pushes the rotor tightly into contact and a handle 136 is affixed non-rotatably to the stem.

Gas flows from inlet 140 to port 141 from which it passes to the groove 142 in rotor 127. The groove may conduct it thence to port 143 or jointly to ports 143 and 144 depending on the position of the rotor. From 143 it may go by way of outlet 149 to a small burner directly. In this embodiment gas from 144 must traverse passage 145 and flow around the end adjacent the diaphragm into a gas chamber 146. A bypass 147 also leads from passage 145 into chamber 146. From here the gas is conducted, subject to diaphragm regulation in the usual manner, to the outlet or high burner supply 148. A plug 150 prevents leakage of gas from the chamber 146 past the loosely fitting valve stem 129.

The automatic return in this modification is provided by a spring pressed pin 155. A boss 156 is built up on the body 125 which is drilled out to house a coiled spring 157 retained in place by a sleeve 158 which screws into place. A collar 159 held in place by a cotter pin 160 bears against the other end of the spring. On rotor 127 is a cam 163 whose face 164 contacts pin 155. The position of the rotor and groove shown in Fig. 8 is for "low" or small burner adjustment. From this position the rotor may be turned counter-clockwise to "off" position without pressure from the spring pressed pin which stops when the collar 159 hits the shoulder 165 formed in boss 156. Gas at "off" position fills the groove but it is not conducted to any of the outlets.

From the "low" position portrayed the rotor may be turned clockwise to "high" position in which both ports are receiving gas. While the movement is being made from "low" to "high" the face 164 of the cam is continually pressing against the pin 155 which will immediately return the adjustment to "low" if the rotor is manually released. At a point just preceding "high" position the point 166 of the cam passes the point of pin 155 which then slides along the curved wall 167 of the cam where it is incapable of exerting a rotating force though held in a contracted position. Hence the rotor can be retained in a "high" position adjustment until manually changed. On turning the rotor counter-clockwise from a "high" toward a "low" position the pin again exerts its force as soon as the point 166 of the rotor passes the pin in reverse direction and throws it quickly and positively to "low" position.

It will be noted that in this modification the steam pressure control through the diaphragm acts only on the gas travelling to the large outlet while the small outlet is unaffected. Other combinations of control can be readily conceived from the above, and it is the intent of this invention to cover such variations in principle of which the described modifications represent a few examples. The pressure shut-off is customarily for

steam but other fluid or liquid pressures are readily applicable and the combination of pressure control and the rotor valve principle are completely operable independent of automatic mechanical features.

There has thus been invented and described a rotor valve containing a steam pressure regulator from which a number of gas outlets can be supplied and regulated, either separately or jointly, and in which adjustments between two or more positions can be automatically made or prevented.

We claim:

1. A combined rotor valve and pressure shut-off comprising a valve body and a rotor housed within said body, a fluid chamber within said body, a passage for fluid therethrough, a base member forming a pressure chamber separated from said body by a diaphragm, said rotor being positionable to selectively conduct gas to a plurality of outlets, said diaphragm being positionable against said passage to effect closure thereof; a handle attached to said rotor engageable in stops at predetermined positions of said rotor, a power means operable on said rotor between certain stops to effect return of said rotor to a selected position and inoperative between other stops.

2. A combined rotor valve and steam pressure shut-off comprising a body and a rotor housed within said body, a gas chamber within said body having an inlet means and an outlet means, a base member forming a steam chamber attachable to said valve, said steam chamber separated therefrom by a diaphragm, said gas outlet means comprising a passage in said rotor, an aperture in the face of said rotor and a series of ports opening through said body; said rotor being positionable to selectively conduct gas to said ports, a bypass connecting the gas chamber with the aperture, said diaphragm being positionable against said passage to effect closure thereof.

3. A combined rotor valve and pressure shut-off comprising a base member, a body member separated therefrom by a diaphragm, a rotor, a fluid inlet to said body communicating with an aperture in said rotor, said aperture being positionable with said body member to communicate successively with a low burner port and a high burner port therein; said low burner port connected with an outlet, said high burner port communicating with a fluid chamber within said body through a passage whose open end lies adjacent said diaphragm, a bypass between said passage and said chamber, said diaphragm being subject to displacement against the open end of said passage for interruption of the flow of fluid past said end, an outlet from said fluid chamber for the regulated flow of gas.

4. A combined rotor valve and steam pressure shut-off comprising a base member, a body member separated therefrom by a diaphragm and a rotor means; an aperture in the contact face of said rotor, a gas chamber in said body, means for conducting gas through said aperture between said chamber and a series of individual outlet means, said rotor being positionable to establish said aperture as a passage respectively between said chamber and selected arrangements of said individual outlet means; an automatic force acting circumferentially to said rotor means, an element on said rotor means in contact relation with said force, a retreat for said force at a one preestablished position whereat said rotor will retain the position occupied and

before which said rotor is returnable to another preestablished previous position, said circumferential force being inoperative at positions preceding said previous position.

5. A rotor valve comprising a body, a rotor means and means for conducting fluid through said valve, a small outlet means and a large outlet means from said body, said valve having a shut-off position, a small outlet position and a position for said small and large outlets jointly, an automatic detent operable at each of said positions, and an automatic means for preventing the establishment of intermediate positions between the small outlet and joint outlet positions.

6. A rotor valve comprising a body, a rotor means and a pressure shut-off means, means for conducting fluid through said valve, a series of successive outlet means from said body, said valve having a shut-off position and succeeding fixed positions at said successive outlet means, an automatic detent operable at each of said positions, and an automatic means for establishing certain valve preselected positions, operative in one direction and inoperative in the opposite direction from said certain positions.

7. A rotor valve comprising a body, a rotor having several positions and a rotating means for said rotor, said means comprising a stem, a handle, a spring, a coacting latch means on said body and said rotating means for retaining said rotating means in certain preselected positions, said handle pivotally mounted on said stem by a pin eccentrically positioned in said handle, said spring being operable to draw said rotor in sliding contact with said base and simultaneously empress said handle bodily toward a latching position.

8. A rotor valve comprising a body and a rotor means, said means including a rotor, a stem and a handle rotatable with said rotor; said body having a slot therein, a spring anchored to said body having an element thereof translatable along said slot, said rotating means positionable independently of said spring during a preliminary portion of the rotation and engageable with said element of the spring during a secondary portion of the rotation for returning said rotating means to said preliminary portion of the rotation.

9. In combination, a rotor valve means and a pressure control means, passage means for conducting gas through said valve means having an opening adjacent said control means, said control means being movable toward the opening to regulate the capacity of said opening, a large outlet and a small outlet from said valve means, said valve means having a position for opening said small and large outlets jointly, a position for opening said small outlet alone and a shut-off position, an automatic means for establishing one of said positions, operative between certain of said positions and inoperative between others of said positions.

10. In combination, a rotor valve means and a pressure control means, passage means for conducting fluid through said valve means having an opening adjacent said control means, said control means movable to and away from said opening for varying the capacity for flow through said opening to said passage means, said valve means having a position for passing a large quantity of gas, a position for passing a small quantity of gas and a shut-off position, an automatic

return from one of said positions to another of said positions.

11. A rotor valve comprising a body, a rotor means and a pressure shut-off means, passage means for conducting fluid through said body and said rotor means, having an opening adjacent said shut-off means, said shut-off means comprising a diaphragm movable to and away from said opening to regulate the quantity of fluid passing therethrough, a small outlet means and a large outlet means from said body, said valve having a shut-off position, a small outlet position, and a position for said small and large outlets jointly, an automatic detent operative at each of said positions, an automatic yieldable means for preventing intermediate positions between certain of said positions.

12. A sliding valve device comprising a body, a floating rotor, actuating means therefor and passage means for conducting gas through said

body and said rotor, outlet means comprising a plurality of individual outlets supplied by said valve, said rotor being positionable to progressively open said outlets, a pressure regulating means operative at certain positions to vary the capacity of the conducting means, automatic means operable to move the rotor to a position for opening certain of the outlet means.

13. A rotor valve comprising a body, a rotor and a rotating means for said rotor, said means comprising a stem, a handle, a spring and a coacting latch means on said body and said rotating means for retaining said rotating means in any of several positions, said handle pivotally secured to said stem by a pin located eccentrically in said stem, said spring being operable to move said handle bodily to a latching position.
